UNITED STATES PATENT OFFICE.

WILLIAM R. MADDERN AND EDWARD H. HIGBEE, JR., OF ST. LOUIS,
MISSOURI,

DESIGN FOR A SHADE-ROLLER BRACKET.

SPECIFICATION forming part of Design No. 33,779, dated December 25, 1900.

Application filed November 30, 1900. Serial No. 38,273. Term of patent 14 years.

To all whom it may concern:

Be it known that we, WILLIAM R. MADDERN and EDWARD H. HIGBEE, Jr., citizens of the United States, and residents of St. Louis, in the State of Missouri, have invented and produced a new and original Design for a Shade-Roller Bracket, of which the following is a specification.

Reference is to be had to the accompanying drawings, forming a part of this specification, in which similar characters of reference indicate corresponding parts in both views.

Figure 1 is a perspective view of a shade-roller bracket embodying our design, and Fig. 2 is an elevation of the same.

The design presents a body part *a*, essentially rectangular in form, and presenting adjacent to one side edge a bayonet-slot *b*.

Intermediate said slot and the opposite edge of the body appear two openings *c*, and from the upper end of said opposite edge projects a spur-like member *d*.

Having thus described our invention, what we claim as new, and desire to secure by Letters Patent, is—

The design for a shade-roller bracket, as herein shown and described.

In testimony whereof we have signed our names to this specification in the presence of two subscribing witnesses.

WILLIAM R. MADDERN.
EDWARD H. HIGBEE, JR.

Witnesses:

JAS. V. JOHNSTON,
WILLIAM TREFNY.
